UNITED STATES PATENT OFFICE.

THOMAS M. KENNEY, OF BOSTON, MASSACHUSETTS, ASSIGNOR, BY DIRECT AND MESNE ASSIGNMENTS, TO THE KENNEY ELECTRICAL CASH CARRIER COMPANY, OF PORTLAND, MAINE.

CASH SYSTEM.

SPECIFICATION forming part of Letters Patent No. 329,050, dated October 27, 1885.

Application filed April 13, 1883. Renewed April 27, 1885. Serial No. 163,580. (No model.)

To all whom it may concern:

Be it known that I, THOMAS M. KENNEY, of Boston, (Cambridge,) county of Middlesex, State of Massachusetts, have invented an Improvement in Cash Systems, of which the following description, in connection with the accompanying drawings, is a specification, like letters on the drawings representing like parts.

This invention relates to a cash system or apparatus for automatically taking a burden or receptacle containing money from the clerks or salesmen stationed at different parts of a store to the cashier's desk, and then returning the change from the cashier's desk to the clerks from whom the money was originally received.

The apparatus consists, essentially, of a conveying device, shown in this instance as a car, passing the different stations with a continuous movement, and having a series of carriers or picking-up devices for receiving the different packages or receptacles containing the money and memorandum-slips, the said carriers being adapted to hold the packages and convey them along with the car to the cashier's desk or main station, where suitable discharging devices are arranged for causing the said carriers to drop the packages, which are shown in this instance as bags or purses provided with suspending rings or eyes. The carriers consist in this instance of hooks or fingers projecting forward in the direction of the movement of the car, the said hooks being arranged in different positions on the said car, so as to move in different paths, and each station is provided with a delivering device, shown as a similar hook adapted to receive the supporting-eye of the purse and raise it into the proper position to receive the hook of the carrier which enters the said eye, and thus removes it from the hook or finger of the delivery device. The said picking-up hooks or carriers are movable, they being normally held in the proper position to receive and hold the burdens to be conveyed, and they are provided with tripping-fingers, which when they come in contact with fixed tripping projections or discharging device in the movement of the car turn the said hooks so as to

cause them to drop or discharge the burdens held upon them, the said tripping-fingers and projections constituting the discharging mechanism.

At the cashier's desk there is a series of tripping devices, one corresponding to each carrier, so that all the carriers are operated to discharge all the burdens severally supported thereon when the car passes the cashier's desk, which is also provided with a series of delivering devices, one corresponding in position with each carrier, so that the cashier by placing a purse on one of the said delivering devices will cause it to be taken by the corresponding carrier and conveyed thereby toward the different clerks' stations.

Each clerk's station is provided with a delivering and discharging device corresponding in position to one of the carriers of the car, the said tripping or discharging device being passed by the car before the delivering device of the same station, so that as the car passes each station the carrier corresponding to the said station is first tripped to deliver the burden that may then be on the carrier being brought from the cashier's desk, and after being thus tripped passes the delivering device to receive any purse that may have been placed thereon by the clerk to be carried to the cashier's desk.

Figure 1 is a diagram showing the different stations of a cash system embodying this invention; Fig. 2, a vertical section of the carrying device on a larger scale and a portion of the apparatus at one of the clerks' stations; Fig. 3, a rear elevation of the said apparatus at the clerk's station; Figs. 4 and 5, a side elevation and plan view, respectively, of the delivering devices at the clerk's desk, and Fig. 6 a side elevation of the tripping devices and receiving apparatus at the cashier's desk.

The conveying device is shown in this instance as a car, A, traveling on a track, B, (see Fig. 1,) passing through the store in proper proximity to the different clerks' stations, C, and also passing the cashier's desk, D. The conveying device A is shown in this instance as a car guided by two stationary wire rails, b

b', one vertically above the other, which, with suitable supporting brackets, *b² b³*, constitute the track *B*. The said car *A* is provided with grooved wheels *a a'*, running on the said rails *b b'*, the bearings of the said wheel *a* being preferably pressed upon by springs *a²*, so as to keep it in contact with the rail *b* in case the said rails *b b'* are not at exactly uniform distances apart at all points. As shown, in this instance the car *A* is actuated by an electromotor, the rails *b b'* being electrically insulated from one another, as by insulating material *b⁴* in the bracket *b² b³*, the said rails being connected with the opposite poles of a suitable battery or source of electricity, *E*, as indicated in the diagram Fig. 2. The circuit is completed between the rails *b b'* through the actuating electro-magnet *M* of the motor, which may be of any suitable or usual construction, it being shown in this instance as having an armature, *F*, mounted on a shaft, *G*, provided with a fly-wheel, *H*, and pinion *I*, meshing with the gear *K* upon the shaft of the wheel or roller *a*. The said shaft *G* is also provided with a suitable commutator, *L*, by which the circuit is closed while the arms of the armature *F* (shown as four in number) are moving up to the poles of the magnet *M*, and broken when the said arms of the armature have arrived at the nearest point to the said poles and are moving away therefrom by the power stored in the fly-wheel *H*.

It will be seen that the conveying device may be actuated by a mechanical motor or 35 clock-work, and that but one rail may be employed to constitute the track *B*, or that the said track itself may be movable like a belt and constitute the conveying device without departing from the invention. The conveying device or car *A* is provided with a series of picking-up devices or carriers, *c c' c²*, shown as spindles or rods, provided at their ends with hooks or fingers *d*, normally held by the action of springs *e* or equivalents projecting 45 forward and preferably slightly upward in the direction in which the car is moving, the said fingers *d* being at different distances from the said car and at different heights, so that they move in different paths parallel with the track *B*.

Each of the different clerks' or salesmen's stations is provided with a delivering device, shown as a hook or finger, *f*, similar to the one, *d*, mounted upon the end of a rod, *f'*, connected with a slide, *f²*, in a tubular post, *f³*, the said slide being raised or lowered by a suitable knob or handle, *f⁴*, passing through a slot in the said post *f³*, by which the delivering device *f* may be raised and lowered to and 60 from the proper position near the track *B*.

The delivering device when raised is retained stationary by a suitable latching device, shown in this instance as by turning the knob *f⁴* into an offset of the slot in the post *f³*, the 65 said delivering-finger *f* at each station thus being held almost in the path of the finger *d*

of the corresponding carrier on the car, and the position of the delivery device in relation to the track being different at all the stations. Thus, when a money-receptacle, *h*, is hung 70 upon one of the delivering devices *f*, as shown in Figs. 2 and 3, the finger *d* of corresponding carrier will catch the said receptacle, removing it from the delivering-finger *f*, and it will then remain suspended on the finger *d* and be 75 conveyed by the car in its further movement.

The spindles of the carriers are provided with tripping projections *i*, which, if engaged by a stationary tripping device or finger, *k*, Fig. 6, or *k'*, Figs. 2 and 3, will rotate the 80 said spindle, turning the said hooks *d* downward, as shown in Fig. 3, so that the receptacles *h* are discharged therefrom. At the cashier's desk there is a series of the said tripping devices *k*, as shown in Fig. 6, one corresponding to each of the carriers, so that all the carriers are tripped and the receptacles supported thereon discharged when the car arrives at the cashier's desk, a suitable incline or guide, *m*, throwing them toward the 90 cashier.

The post *f³* at each station is provided with a tripping or discharging device, *k'*, for operating the carrier corresponding to the station, so that a receptacle belonging to any station 95 if placed upon the proper carrier will be automatically delivered when arriving at the station, but will pass all the other stations without being disturbed.

The tripping devices *k'* operate at each station before the car arrives at the delivering device thereof, thus permitting the carrier to discharge its load and be ready to receive another, as shown by the full and dotted lines, Fig. 3, as the car passes the station. 100 105

If desired, the supporting-rod, *f'* of the delivery device may be provided with a receiving-finger, *n*, to receive the receptacle when discharged from the carrier *d*. The cashier's desk will be provided with a series of delivering devices, *o*, (see Figs. 4 and 5,) corresponding to the different carriers, upon which the cashier will hang the different receptacles after having made the proper change, they being arranged beyond the discharging devices *k* in 110 the direction of the movement of the carrying device. 115

It is obvious that the apparatus may be varied in many particulars without departing from this invention. 120

If desired, the carriers may be arranged upon both sides of the conveying device, and it will be seen that one carrier may be used to convey all the receptacles from the different stations to the cashier's desk, while independent carriers moving in different paths and corresponding discharging devices will be required only for conveying from the said cashier's desk to the different stations. 125

I claim—

1. The combination of a conveying device and actuating mechanism therefor, by which 130

it is moved past the different stations, with a series of carriers on the said conveying device, and delivering and discharging devices whereby the receptacles are transferred to and removed from the said conveying device, substantially as described.

2. The railway forming a part of an electric circuit, and the conveying device or car, combined with an actuating electromotor for the said car and carriers, and delivering and discharging devices whereby the receptacles are transferred to and removed from the said carriers, substantially as described.

3. The conveying device and a series of carriers moved thereby in different paths, combined with discharging devices at different stations located to operate the different carriers respectively, whereby the burden of each carrier is discharged at the corresponding station, substantially as described.

4. The conveying device and series of carriers moved thereby in different paths, combined with discharging and delivering devices at different stations located to co-operate with each corresponding carrier, the discharging device operating before the delivering device, whereby the carrier may first discharge the receptacle or burden belonging to the said station and then receive a receptacle or burden from the said station, substantially as described.

In testimony whereof I have signed my name to this specification in the presence of two subscribing witnesses.

THOMAS M. KENNEY.
